United States Patent Office

Des. 217,873
Patented June 23, 1970

217,873

GOLF CLUB HEAD

Thomas Currie Steele, 94 Rosslyn Ave.,
Rutherglen, Lanarkshire, Scotland

Filed Apr. 17, 1969, Ser. No. 16,802

Claims priority, application Great Britain Oct. 22, 1968

Term of patent 14 years

Int. Cl. D21—03

U.S. Cl. D34—5

FIG. 1 is a perspective view of a golf club head showing my new design;

FIGS. 2 and 3 are elevations taken from the front and rear;

FIGS. 4 and 5 are end elevations; and

FIGS. 6 and 7 are plan views from above and below respectively.

I claim:

The ornamental design for a golf club head, as shown.
